WILLIAM F. BRACHER, OF SAN JOSE, CALIFORNIA.

MOTOR-CYCLE TANDEM ATTACHMENT.

1,000,771.

Specification of Letters Patent. Patented Aug. 15, 1911.

Application filed December 29, 1910. Serial No. 599,849.

To all whom it may concern:

Be it known that I, WILLIAM F. BRACHER, a citizen of the United States, and a resident of San Jose, county of Santa Clara, and 5 State of California, have invented certain new and useful Improvements in Motor-Cycle Tandem Attachments, of which the following is a specification.

My invention is an improvement in motor 10 cycle tandem attachments, and consists in certain novel constructions and combinations of parts hereinafter described and claimed.

The object of the invention is to provide 15 an attachment of the character specified, by means of which the ordinary single passenger motor cycle may be converted into a two-passenger vehicle with the seats tandem without any changes in the structure of the vehicle itself. Referring to the drawings 20 forming a part hereof, Figure 1 is a perspective view of the detached improvement, and, Fig. 2 is a side view of a motor cycle with the improvement in place.

The embodiment of the invention shown 25 in the drawings, consists of a yoke comprising a body portion 1, and arms 2, and supporting a seat 3, together with means for attaching the yoke to the frame 4 of the motor cycle.

30 The seat 3 is connected to one end of a seat post 5, in the usual manner, and the seat post is provided at the other end with a bearing ring 6, encircling the body 1 of the yoke, and secured to the said body in any 35 suitable manner, as, for instance, by brazing or soldering.

A plate 7 is slidably connected with each 40 of the arms of the yoke. Each plate is provided at each of its ends with a laterally extending lug 8, and each lug is provided with a bearing 9 to receive the arm. The body portion of each plate is on the inner side of the arm, and each plate is provided near its lower end with an opening 10.

45 A coil spring 11 encircles each arm of the yoke below the uppermost lug 8, and a collar 12 is arranged on the arm intermediate the lugs 8, and is held in adjusted position by a set screw 13. The lower end of the spring 50 is secured to the collar, and the upper end is secured to the under face of the lug. Another coil spring 14, of lesser length than the spring 11, encircles each arm below the lowermost lug 8, and a collar 15 is slidable 55 on the arm below the spring. The collar is held in adjusted position by a set screw 16,

and the spring rests on the collar and bears against the lower face of the lug.

An arm 17 is secured at one end at 18, to each of the plates 7, near the upper end of the plate, and near its opposite end each arm is provided with a transverse groove 19. A strap 20 provided with a transverse groove 21, is detachably connected with the end of the plate by screws 22. The grooves 19 and 21 coöperate to form an opening for receiving one arm of the rear fork 23 of the frame of the cycle, and the arm and strap form a sectional bearing which may be detachably connected with the fork. The arms 17 are 60 connected intermediate their ends by a yoke, the arms 24 of which are connected with the respective arms 17, by rivets 25. A split ring 26 is rigidly connected with a post 27, on the body portion 28 of the yoke, and a 65 handle bar 29 is held in the ring, by means of a screw 30, engaging the ends 31 of the ring. A foot support or rest 33 is arranged on each arm 2 below the plate, each rest consisting of a plate having a hub 34 encircling the arm, 70 and the outer end of the plate is upturned, as shown at 35. The rests are oppositely arranged, both extending outwardly, and each is held in place by a collar 36, encircling the arm below the rest, and held in adjusted position by a set screw 37. The attachment is 75 connected to the cycle, with the arms 2 of the yoke astride the rear wheel 38. The handle bar supporting yoke 24—28 also rests astride the wheel, and the sectional bearing 80 of each of the arms 17 is connected to the adjacent arm 23 of the rear fork. The material of the yoke 1—2 is sufficiently resilient to permit the arms to spread enough to engage the axle ends with the openings, 10 and 85 90 95 90 the attachment is supported on the axle ends and by the arms 17.

The foot rests 33 may be moved toward or from the seat 3, to accommodate riders of various heights, and the tensions of the supporting springs 11 and 14, may be varied to suit the weight of the rider. To adjust the foot rest, the screw 37 is loosened, and the collar 36 and rest 33 are moved up or down on the arm. When in the proper position, 105 the screw 37 is tightened to hold the collar rigid. The tension of the springs 11 and 14 is varied by raising or lowering the collars 12 and 15, respectively. The rigid connection of the arms 17 with the plates, holds 110 the frame rigidly connected with the frame of the cycle.

The attachment is simple and inexpensive, and may be easily attached and detached. No change is necessary in the construction of the cycle, and the device cannot get out of order. To remove the attachment, the bearings are loosened from the arms of the rear fork, and the arms 2 of the yoke are sprung apart slightly to disengage the axle ends from the openings 10.

10 I claim:

1. An attachment of the character specified, comprising a yoke consisting of a body and arms, a seat post extending upwardly from the body, a seat on the post, a plate 15 arranged on the inner side of each arm of the yoke, each plate having an angular perforated lug at each end for receiving the adjacent arm of the yoke, a collar slidable on the arm below each of the lugs, a spring 20 encircling the arm between each lug and the collar below the same, the upper spring being connected at its ends to the lug, a set screw traversing each collar and engaging the arm for holding the collar in adjusted 25 position, each of the plates having an opening near its lower end for receiving the end of the rear axle of a motor cycle, an arm secured at one end to each plate near its upper end, the opposite end of each arm being provided with a sectional bearing for 30 engaging an arm of the rear fork of the motor cycle, a yoke connecting the arms, a post extending upwardly from the yoke, a handle bar connected with the post, a foot 35 rest for each arm, each rest having a hub slidable on the arm, a collar below each rest, and a set screw for holding the collar in adjusted position.

2. An attachment of the character specified, comprising a yoke consisting of a body portion and arms extending substantially parallel with each other, a seat connected with the body of the yoke, a plate on the inner side of each arm, each plate having 45 a lateral perforated lug at each end for receiving the arm, a spring encircling the arm below each lug, a collar slidable on the arm below each spring, means for securing each collar in adjusted position, each of the 50 plates having an opening near its lower end for receiving one end of the rear axle of a motor cycle, an arm secured at one end to each plate near its upper end, each arm having a sectional bearing at its opposite 55 end for engaging the rear fork of the cycle, a yoke connecting the arms intermediate their ends, a handle bar on the yoke, a foot rest slidable on each arm of the yoke, and means for securing each rest in adjusted 60 position.

3. An attachment of the character specified, comprising a yoke consisting of a body portion and arms extending substantially parallel with each other, a seat connected 65 with the body of the yoke, a plate on the

inner side of each arm, each plate having a lateral perforated lug at each end for receiving the arm, a spring encircling the arm below each lug, a collar slidable on the arm below each spring, means for securing 70 each collar in adjusted position, each of the plates having an opening near its lower end for receiving one end of the rear axle of a motor cycle, an arm secured at one end to each plate near its upper end, each arm 75 having a sectional bearing at its opposite end for engaging the rear fork of the cycle, a connection between the arms intermediate their ends, a handle bar on the connection, and a foot rest adjustably mounted on each arm.

4. An attachment of the character specified, comprising a yoke consisting of a body and laterally extending substantially parallel arms, a seat on the body of the yoke, a 85 plate on the inner side of each arm, and provided with an opening near its lower end, each plate having a lateral perforated lug at each end for receiving the arm, a collar slidable on the arm below each lug, means 90 for holding each collar in adjusted position, a spring, between each collar and the lug above the collar, an arm secured at one end to the upper end of each plate and provided at its opposite end with a sectional bearing, 95 a connection between the arms intermediate their ends, a handle bar on the connection, and a foot rest adjustably mounted on each of the arms.

5. An attachment of the character specified, comprising a yoke consisting of a body and laterally extending substantially parallel arms, a seat on the body of the yoke, a plate on the inner side of each arm, and provided with an opening near its lower 100 end, each plate having a lateral perforated lug at each end for receiving the arm, a collar slidable on the arm below each lug, means for holding each collar in adjusted position, a spring between each collar 105 and the lug above the collar, an arm secured at one end to the upper end of each plate, and provided at its opposite end with a sectional bearing, a handle bar connected 110 with the arms intermediate their ends, and a foot rest adjustably connected with each arm 115 of the yoke.

6. An attachment of the character specified, comprising a yoke consisting of a body and laterally extending substantially parallel arms, a seat on the body of the yoke, a plate on the inner side of each arm, and provided with an opening near its lower end, each plate having a lateral perforated 120 lug at each end for receiving the arm, a spring below each lug and upon which the lug rests, means for varying the tension of each of the springs, an arm secured at one end to each plate near its upper end and having a sectional bearing at its opposite 125 end.

130

- end, a handle bar connected with the arms intermediate their ends, and a foot rest adjustable on each arm of the yoke.
7. An attachment of the character specified, comprising a yoke consisting of a body and laterally extending substantially parallel arms, a seat on the body of the yoke, a plate on the inner side of each arm, and provided with an opening near its lower end, a 5 slideable connection between each plate and the adjacent arm, a yielding support for the plate between the plate and the arm, means for varying the tension of the support, an arm secured at one end to each plate near its upper end and having a sectional bearing at its other end, a connection between the arms intermediate their ends, a handle bar on the connection, and a foot rest adjustable on each arm of the yoke.
- 10 8. An attachment of the character specified, comprising a yoke consisting of a body and arms, a seat on the body, a plate on the inner side of each arm and slidably connected therewith, and having an opening near its lower end, a yielding support for each plate between the plate and the arm, 15 means for varying the tension of the support, an arm secured at one end to each plate near its upper end, and having a sectional bearing at its other end, a handle bar supported on the arms intermediate their ends, and a foot rest on each arm of the yoke.
